ATTORNEY

UNITED STATES PATENT OFFICE

PHILIP S. DOUMITT, OF CLATSASKIE, OREGON

ARCH SUPPORT

Application filed March 30, 1931. Serial No. 526,169.

This invention relates generally to supporting devices for the feet and particularly to an improved arch support.

The main object of this invention is to provide an improved form of arch support which will have a wide range of adjustment and to make it possible to support the foot at the precise point and in the degree required.

The second object is to provide a unitary structure which is so arranged that the manufacturer need concern himself only with providing a variety of sizes corresponding with shoe sizes, leaving it to the specialist, the shoe salesman or the user to insert or shift the filling materials to meet the requirements.

The third object is to provide a special form of metatarsal pad for use in connection with the arch support.

The fourth object is to so construct the arch support as to make it possible to easily narrow the shoes at the arches, to provide longitudinal arch corrections, as well as to provide all necessary corrections for the heels.

These, and other objects, will become more apparent from the specification following, as illustrated in the accompanying drawing, in which:

Fig. 1 is a bottom view of the arch support.
Fig. 2 is a plan of the arch support.

Fig. 3 is similar to Fig. 2, but showing additional heel padding inserted from the top side.

Fig. 4 is a section taken along the line 4—4 in Fig. 2, illustrating the form the device may assume within the shoe under the pressure of the foot.

Fig. 5 is a section taken along the line 5—5 in Fig. 2.

Fig. 6 is a perspective view of the metatarsal pad with parts broken away in section.

Fig. 7 is a perspective view showing the

device and its relation to the foot of the wearer.

Similar numbers of reference refer to the same or similar parts throughout the several views.

The device consists of a relatively thick and stiff insole for the rearmost portion of the shoe including the heel and extending in front of the metatarsal joint. This insole 10 may be of all leather or laminated leather and fabric joined by a suitable adhesive. On the top side of the insole 10 is placed a cover 11 of smooth, pliable material, preferably leather, and departing from the shape of the insole 10 in two particulars only; the first forming a somewhat rectangular extension 12 which is formed on the outer side of the support. The word "outer" is used with relation to the foot under which this support is worn.

On the under side of the extension 12 is secured a somewhat rectangular piece of soft leather 13 which forms a bottom for the extension flap 12. The piece 13 is provided with a longitudinal slit 14. The piece 13 is secured to the extension flap 12 by means of a continuous seam 15. A soft padding such as floss 16 is inserted through the slit 14 to provide the desired thickness which obviously has the effect of narrowing the shoe at the arch.

The second difference between the shape of the insole 10 and the cover 11 is over the curved inner edge 17 of the insole 10 where the cover 11 is provided with an outwardly curving flap 18. On the under side of the insole 10 is secured a series of longitudinal arch-correcting pads 19, 20 and 21 which are somewhat similar in shape although of diminishing size with the smallest pad 19 lowest. Each of the pads 19, 20 and 21 is made of two plies of leather which are united around their edges and secured to the insole 10 by means of their respective seams 22. Each of the pads 19, 20 and 21 is provided

with a slit 23 which extends longitudinally through the lower ply of its respective pad. Each of the pads 19, 20 and 21 may be padded through the slits 23 and will contain 5 more or less floss 24 to meet the requirements. The floss is inserted after the support is built.

On the under side of the heel portion of the insole 10 is secured a thin leather heel 25. Under the heel 25 is secured a horseshoe 10 shaped heel seat 26 which is stitched to the heel 25 by two rows of stitching 27. The heel seat 26 is provided with a plurality of slits 28 through which floss 29 may be inserted into the heel seat. The entire heel 25 15 is now secured to the insole 10 by means of the seam 30 which extends entirely around the heel 25. A longitudinal seam 31 along the center line of the heel 25 also assists in securing the heel to the insole 10, but its primary purpose is to divide the heel into two sections to which access is gained through the slits 32 parallel to and on opposite sides of the seam 31. Floss 33 may be inserted 20 through the slits 32 for the purpose of correcting a tendency to wear the heel of the shoe unevenly. Strictly speaking, it is to correct the tipping of the heel of the foot which causes the heel of the shoe to wear out on one side.

30 It will be noted that the cover 11 is secured to the insole 10 along its forward edge by means of the seam 34 providing an open pocket between the members 10 and 11 behind the seam 34. It is in this pocket that 35 the metatarsal pad shown in Fig. 6 is placed. This pad consists of a somewhat heel-shaped two-ply pad 35 whose under side 36 is provided with a slit 37 for the insertion of the floss 38. On the side of the pad 35 opposite 40 the side 36 is secured a smaller pad 39 which is provided with a slit 40 for the insertion of floss 41. The side 42 of the pad 35 conforms somewhat to the curvature of the seam 34 (as shown in Fig. 2).

45 In order to definitely locate the metatarsal pad a thumb tack is inserted through the slit which embeds itself in the insole 10 as soon as pressure is brought to bear upon the cover 11.

50 In the form shown in Fig. 3 the slits 28 and stitching 27 pass through the top cover 10, which is advantageous under certain conditions. Obviously, when used on the top side of the device they are unnecessary on the 55 bottom thereof.

It can be seen from the foregoing that while this construction is relatively simple, it provides a wide range of adjustment in the shape and size of that portion of the shoe 60 which most seriously affects the comfort of the wearer.

In some instances it may be found desirable to permanently locate the metatarsal pad by sewing a seam around same, thereby fastening 65 it to either or both the insole 10 and the

cover 11. Obviously, the enclosed area must be padded to suit the needs of the wearer, and this is accomplished by forming a flap in the insole portion of the pad for the introduction of suitable padding material. In this form of the device the separate pad shown in Fig. 6 is not required.

With this construction it is desirable to extend the seam 34 clear around the edges of the insole, that is, joining with the seam 25. Otherwise, the construction is identical with the first described form of the device.

Attention is drawn to my copending application, Serial Number 455,890, over which this device is an improvement.

I claim:

1. A longitudinal arch-correcting device consisting of an insole having a plurality of separately fillable pads mounted in superimposed relationship on the under side of the shank portion of the arch support and projecting outwardly from the outer line of said shank portion of the insole.

2. An arch correcting device consisting of an insole having a plurality of pads secured on the under side thereof, each of said pads having openings at intermediate portions thereof for the insertion and distribution of the filling, and having the periphery of each pad closed.

3. An arch support consisting of an insole having a somewhat rectangular shoe-narrowing flap secured along the outer edge of one side of the insole adjacent the shank portion of the arch support, and a plurality of superimposed longitudinal arch-correcting pads secured under the said shank portion and extending laterally and upwardly along the inner side of the foot.

4. An arch support consisting of an insole having a flexible heel secured thereto, said heel having a horseshoe-shaped heel seat secured around the curved portion thereof, the area within said heel seat having a longitudinal subdividing seam and having slits formed along opposite sides thereof for the introduction of padding, said horseshoe-shaped heel seat also having slits formed therein for the introduction of padding within the heel seat portion of the device.

5. An arch support consisting of a relatively stiff insole, a flexible cover for said insole having a somewhat rectangular shoe-narrowing flap extending from one side thereof opposite the shank portion of the arch support, a cover for said flap outside of said insole, said cover having a slit formed therein for the introduction of padding, and a metatarsal pad between said insole and cover.

6. A metatarsal pad consisting of a three-ply heel-shaped pad having a continuous seam around the edge thereof, the outer plies of said pad having slits formed therein for the introduction of padding and means for

securing said pad in position under the metatarsal joint.

7. An arch support consisting of an insole for the shoe having the toe portion cut away and rounded directly in front of the metatarsal joint, a cover for said insole secured thereto around the curved portion of the heel and along the rounded portion of said front edge, said cover extending laterally beyond the boundaries of said insole at the shank portion thereof, said cover having a pocket formed along one side thereof within the area extending beyond said insole.
